TOILET SEAT

Alexander Schwartz, New York, N. Y.

Application January 8, 1940, Serial No. 312,901

4 Claims. (Cl. 4—237)

My invention relates to toilet seats and has particular reference to toilet seats and covers made of corrugated paper.

My invention has for its object to provide a light and inexpensive seat made of an ordinary corrugated board by winding a strip of such board on a suitable form or mandrel, the width of the strip corresponding to the thickness of the board, so that the corrugations of the board extend transversely of the board. Due to such arrangement of the corrugations, the board, when finished, is very strong and resistant to bending and warping. Being soundproof, the seat or cover made by this method does not produce any objectionable noise when dropped on its place over a toilet bowl and cannot possibly damage the latter.

Another object of my invention is to provide means to close the spaces between the corrugations at the surface of the board in order to obtain a substantially smooth and continuous surface, suitable for enameling or covering with a layer or film made of a smooth waterproof material such as "Celluloid," etc. I attain this object by employing corrugated board comprising a flat sheet of relatively stiff or hard paper to which a corrugated sheet is glued, the latter being made of relatively soft paper. The seat or cover, when fully wound, must be trimmed or milled so as to obtain the required shape with rounded edges. Instead of trimming the edges by ordinary methods such as are employed in woodworking industries, as by cutting with rotary knives, I employ grinding, filing or rasping tools for this purpose.

It should be noted that ordinary cutting or trimming operations remove uniformly both the flat and corrugated paper, leaving holes between the corrugations which must be filled by a suitable plastic or cementitious material in order to obtain a smooth surface.

I have found, however, that my grinding or rasping tools, while smoothly removing the edges of relatively stiff, flat paper, do not fully remove the exposed portions of the relatively soft corrugated paper, but largely mash and spread the edges until they completely fill the spaces between the corrugations at the surface of the article. By continuing the rasping or grinding operation after the spaces between the corrugations are filled, a substantially smooth and uninterrupted surface is obtained which can then be made waterproof by ordinary methods and finally enameled or covered with a sheet of "Cellu-

loid" or similar smooth and waterproof material.

Another object of my invention is to provide means to wind the corrugated strip in such manner that the seat will have an oval shape inside while on the outside its one end will be substantially straight as required for attaching hinges. I have found that the most satisfactory method of obtaining such a result is by winding separately the inner and outer portions of the seat or cover and joining together the two portions. The outer portion is wound on an oval mandrel or form of a required shape, having one end cut off to make it substantially straight, and the inner portion is wound on an oval mandrel or form so as to obtain an oval opening in the center. The peripheral contour of the inner portion is made to correspond to the inner contour of the outer portion except where the latter is straightened out at the end. The inner portion has one end partly cut off to make it fit the inner straight end of the outer portion. The inner portion is inserted into the outer portion and is cemented in its place.

My invention is more fully described in the accompanying specification and drawing, in which:

Fig. 1 is a top plan view of my seat partly in section;

Fig. 2 is a view of an outer portion of the seat partly completed;

Fig. 3 is a similar view of an inner portion;

Fig. 4 is a top plan view of a cover partly in section;

Fig. 5 is a fractional sectional view of the end portion of the seat showing attachment of a hinge;

Fig. 6 is an enlarged detail view of an edge portion of my seat or cover partly finished on the surface; and

Fig. 7 is a view of a finishing tool partly in section in connection with a portion of my seat or cover.

Fig. 8 is a detail view of a hinge attachment.

My toilet seat consists of two portions 1 and 2 as shown in Figs. 1, 2 and 3. These portions are made of long strips of corrugated board wound on a suitable mandrel or form which is removed upon completion of the winding. The corrugated board consists of a flat sheet 3 of a relatively thin and stiff paper and a corrugated sheet 4 of a relatively soft and flexible paper which is glued to the surface of the flat sheet. The strips are so cut that the corrugations extend

transversely as shown in Fig. 5. The board made of such corrugated board is therefore highly resistant to compressive and bending stresses as well as warping, being at the same time very light. The successive turns of the strip are glued together in the process of winding the seat or cover, the starting end 5 being trimmed or scarified to provide a smooth surface.

The mandrel for the outer portion 1 is flattened at one end as shown in Fig. 2, so that the outer portion 1 has also a flattened or straight end

portion at 6 inside and at 7 outside, as is necessary for attaching hinges 8 (Fig. 5). The mandrel is of an oval shape so that the inner portion has an oval opening in the central portion. The shape of the mandrel is such that the outer contour of the portion 2 exactly corresponds to the inner contour of the outer portion 1 with the exception of its flattened or straightened end.

In order to make the portion 2 fit in the opening in the portion 1, the end of the portion 2 is cut off at 8 as shown in dotted lines in Fig. 3.

The inner portion is then inserted into the outer portion and is cemented or glued in its place

inside the outer portion. Both portions can be wound in the same manner, with the corrugated paper to the inside as shown in Fig. 2. The excess corrugated strip may be then removed from

the inner side of the portion 2. It is also possible, of course, to wind the inner portion with

the flat side of the corrugated board to the inside, gluing together the corrugated strips 6 at the place of joint of the two portions, or remov-

ing one of the strips 6 to facilitate the gluing of the two portions.

For attaching the hinges 8, inserts 9 are fitted into the board. The latter is drilled for this

purpose edgewise as shown in Fig. 5, or transversely as shown in Fig. 8, the inserts being cemented or glued in the drilled holes. The inserts may be made of a suitable machinable material such as wood or a plastic composition, and are drilled and tapped for screws 10 with which

the hinges 8 are attached.

The cover, Fig. 4, is made in a similar manner and consists of the portions 11 and 12, wound separately and glued or cemented together as

described. The only difference is that the inner portion 12 is wound on a relatively small mandrel 13 made of a machinable material, which is permanently cemented in its place so that the board has no central opening.

The seat, when completed, is trimmed on the outside in order to provide it with rounded edges. I have found that very satisfactory results are obtained by grinding or milling the edges of the board and its surface with special rotary tools 14, Fig. 7. The tool is made in the form of a milling cutter of a required shape and is provided on its surface with a plurality of small sharp projections 15 of the substantially same shape as are formed on ordinary rasps or coarse files.

The sharp points of the projections 15 remove particles of material from the surface of the board, the particles being then immediately thrown out by centrifugal force, so that the tool remains clean and free from clogging by the removed particles.

I have also found that this tool can be used to advantage for closing the spaces between the corrugations at the surface of the board. I use for this purpose the corrugated paper which has a relatively thin and stiff flat paper 5 and relatively soft and thick corrugated strip 6. The

flat paper 5 is ground clean and smooth by the tool, while the corrugated strip, being rather soft, becomes largely mashed and spread around, completely filling the spaces between the corrugations, as shown in Figs. 6 and 7. The flat side of the seat can be ground in a similar manner by using a flat round rasp-like tool. The surface of the seat, when trimmed or ground by my tool, becomes smooth and continuous, without any holes which are closed by the expanded edges of the corrugated strip 6. The surface can be then sprayed or otherwise covered with a suitable hardening substance such as glue or liquid glass. It may be finally polished when dry and covered with a suitable enamel, or a separate envelope may be attached to the surface, molded of a suitable plastic composition like "Celluloid," fiber, etc. The surface, when so treated, becomes very hard and firm, resisting cracking or warping. The expanded portions 16 become very strong when impregnated and, being integrally formed with the board 6, firmly resist cracking and breaking out as may be the case when the clearances are filled with a plastic material.

It should be noted that since the method of construction of the seat and cover is substantially the same, the foregoing explanations and statements regarding the seat are also applicable to the cover.

A cover 17, Fig. 5, may be cemented to the seat, if desired. The cover can be made by molding from a suitable sheet material, such as "Celluloid," etc.

It is understood that my toilet seat may be modified without departing from the spirit of the invention, as set forth in the appended claims.

I claim as my invention:

1. A toilet seat made of a strip of corrugated board with corrugations extending transversely of the strip, wound flatwise in a series of successive turns glued together so as to form a flat object of a thickness corresponding to the width of the strip the corrugations forming air ducts across the product, the edges of the strip in the board being roughened and expanded so as to fill the air ducts between the corrugations at their ends, thereby forming a substantially continuous surface.

2. A toilet seat comprising an inner and an outer portion made of strips of corrugated board wound flatwise, the thickness of the seat corresponding to the width of the strip, the successive turns of the strip being glued together, the outer portion being formed of substantially continuous turns so wound as to form a desired outer contour, the inner portion having substantially continuous inner turns wound to provide an inner contour different from the contour of the outer portion, the outer turns of the inner portion being made discontinuous by trimming to correspond to the inner contour of the outer portion, the inner portion being fastened in its place in the opening in the outer portion.

3. A toilet seat made of a strip of corrugated board with corrugations extending transversely of the strip, wound flatwise in a series of successive turns glued together so as to form a flat object of a thickness corresponding to the width of the strip, the corrugations forming air ducts extending across the object, the ends of the ducts being closed by a filling material and cemented, the filling material partly extending into the ducts, thereby forming a substantially continuous surface, the seat being provided with holes at one end extending from its edge in direction 75

parallel to its surface across the corrugations, and inserts placed in the holes adapted to receive screws for fastening hinges.

4. A toilet seat made of a strip of corrugated board with corrugations extending transversely of the strip, wound flatwise in a series of successive turns glued together so as to form a flat object of a thickness corresponding to the width

of the strip, the corrugations forming straight air ducts extending from one side of the object to the other, means to close the air ducts at the ends so as to form a substantially continuous surface, and inserts adapted to receive screws for hinges, the inserts extending substantially transversely of the corrugations. 5

ALEXANDER SCHWARTZ.
